CLAIM

I claim the ornamental design for an adjustable tree limb support, as shown.

DESCRIPTION

FIG. 1 is a front perspective view of the adjustable tree limb support showing my new design;

FIG. 2 is a rear perspective view thereof;

FIG. 3 is a back elevational view thereof;

FIG. 4 is a right side elevational view thereof;

FIG. 5 is a front elevational view thereof;

FIG. 6 is a left side elevational view thereof;

FIG. 7 is a bottom plan view thereof; and,

FIG. 8 is a top plan view thereof.
